VACUUM CLEANER

Lewis C. Packer, Longmeadow, Mass., assignor to Westinghouse Electric & Manufacturing Company, East Pittsburgh, Pa., a corporation of Pennsylvania

Application January 3, 1935, Serial No. 233

3 Claims.

(Cl. 240—2)

My invention relates to vacuum cleaners and particularly to illuminating devices mounted thereon.

An object of my invention is to provide a relatively simple and compact assembly of a vacuum cleaner and a pair of incandescent lamps mounted thereon.

Another object of my invention is to provide a relatively simple and easily and quickly assembled and disassembled lamp-supporting structure mounted on a vacuum cleaner in such position as to be protected thereby.

Other objects of my invention will either be apparent from the following description of a preferred form of device embodying my invention or will be specifically pointed out during the course of such description.

In practicing my invention, I provide, in combination with a vacuum cleaner assembly embodying a fan casing and a nozzle casing operatively associated with and extending angularly relatively to each other, with a pair of tubular lamp-supporting casings located in the corners formed by the associated fan and nozzle casings. 25 In each such tubular auxiliary casing I locate an incandescent lamp-supporting structure, a reflector, a lens and a means for holding the lens in front of the lamp.

In the single sheet of drawings,

30 Figure 1 is a view in front elevation of a vacuum cleaner embodying my invention.

Fig. 2 is a view in side elevation thereof with a portion shown in section, which section is on the line II—II of Fig. 1, and

35 Figs. 3 to 7, inclusive, are views in side elevation and in section respectively of parts of the lamp structure.

Referring first to Figs. 1 and 2, of the drawing, I have there illustrated a vacuum cleaner 11 which includes a nozzle casing 13 which may be integral with a blower or fan casing 15 and which is operatively secured in any suitable or desired manner against the front end of a motor housing 17 having located therein a motor for driving or operating a fan in order to create a suction in the nozzle casing 13 and more particularly in the mouth 19 thereof.

I have elected to show the outlines only of the motor housing and of the nozzle and fan casing, since the parts more particularly embodying my invention are operatively associated with the nozzle casing and may be applied to more or less standard vacuum cleaner assemblies. A rotary brush 21 is located in the mouth 19 of the 55 nozzle casing 13 and may be driven by any suit-

able or desired means well known in the art such as by the fan motor. Front supporting wheels 23 are provided, as well as one or more rear supporting wheels 25, all in a manner well known in the art. A handle is operatively associated with and pivotally mounted on the motor housing 17 and is indicated by a fork 27 in Fig. 2 of the drawing, a latch plate 29 cooperating with the handle to hold it in substantially vertical position when desired. The motor may be energized through a twin conductor cord indicated generally at 31, which ends in a connecting plug 33 adapted to interfit with a connecting socket mounted in and protected by a small auxiliary casing 35, all in a manner now well known in the art. A rubber bumper 37 may be located around the nozzle casing 13 and a bumper plate 39 may be located centrally of the nozzle casing.

Referring now to the parts more particularly embodying my invention, a pair of tubular auxiliary casings 41 are provided which, in the structure shown in the drawing, are made integral with the nozzle casing 13 at the rear portion thereof and extend rearwardly of a lateral wall 43 of the nozzle casing 13.

I wish to point out more particularly that I locate the auxiliary casings 41 in the corners formed by the laterally extending nozzle casing 13; and the downwardly extending fan casing 15 where the incandescent lamp structure to be hereinafter described will be protected against accidental engagement with furniture of all kinds when the vacuum cleaner is in actual use. Thus, it will be noted that as far as lateral protection thereof is concerned, the auxiliary casings 41 are located well within the lateral side portions of the nozzle casing, as will be seen more particularly by reference to Fig. 1 of the drawing. It is also evident that they are protected by the upper portion of the fan casing 15. Referring to Fig. 2 of the drawing, it will be noted that the casings 41 are located well back of the forwardly extending portion of nozzle casing 13 and more particularly of the bumper 39, so that if the forwardly extending portion or portions of the nozzle casing should be accidentally brought into engagement with a piece of furniture, the bumper 39 will take the shock to thereby protect the incandescent lamp assemblies located in auxiliary housings or casings 41.

Each of the auxiliary casings 41 is provided with an inner annular shoulder 45 and an outer or forward annular shoulder 47. A lamp supporting structure of the kind shown in Fig. 3 of the drawing may include a lamp socket 49 55

adapted to receive and support an incandescent lamp 51 and preferably provided with an annular flange 53, which flange has a pair of openings extending therethrough to receive small 5 clamping screws 55 which extend therethrough and into the wall of the shoulder 45, as will be seen more particularly by reference to Fig. 2 of the drawing.

A dished reflector 57 has an opening therein 10 large enough so that the bulb of lamp 51 may be moved therethrough and is also provided with an outer annular flange 59 which is adapted to be located against the front face of the wall of shoulder 47, as will be noted by reference to Fig. 15 2 of the drawing. A split spring ring 61, which constitutes a spacing ring, is located immediately in front of the dished reflector 57 and is provided with a plurality of radially-inwardly extending lugs 63 which engage the inner flat 20 surface of a lens 65. A tubular lens supporting and securing member 67 is provided, whose forward edge portions are rolled or return bent inwardly as is shown more particularly in Fig. 7 of the drawing, so that the front arcuate surface 25 of the lens 65 may engage the inwardly rolled portion 69, as may be seen by reference to Fig. 2 of the drawing. The tubular support 67 is provided with a plurality, preferably three, indentations 71 against which the rear edge of spring 30 ring 61 may rest, as is also shown in Fig. 2 of the drawing, to thereby hold the lens 65 in the position shown in Fig. 2 of the drawing.

Means for holding the tubular member 67 in its proper operative position in close engagement 35 with the front surface of flange 59 includes a spring latch 73, of substantially L-shape, whose rear end portion is clamped against the front surface of flange 53 by one of the securing screws 55. The forward end of spring latch 73 is provided with an indented portion 75 which is adapted to fit into one of the indentations 71 in ring 61, to thereby hold member 67, lens 65 and spring ring 61 in close operative engagement against the front face of flange 59 of reflector 40 45 57 and to thereby hold the latter also in its proper operative position.

I prefer to use lamp bulbs 51 adapted to operate at lower than standard line voltages, and I may use 6 volt bulbs and connect the two 50 bulbs in series-circuit relation relatively to each other by means of the conductors 77 shown in Fig. 3 of the drawing, and by other conductors not shown. A copending application Serial No. 1,131, filed January 11, 1935 by R. H. Jordan, 55 and assigned to the same assignee as is the present application, discloses a means for energizing the two incandescent lamps and reference may be had to that application for the details of the source of supply of electric energy for energizing the lamp bulbs 51. However, I desire it to 60 be understood that I do not wish to be limited to such source of electric energy for the illuminating means, since it is possible to use normal voltage incandescent lamps and to make the

proper arrangements for energizing them from the same circuit as is the motor located in motor housing 17, that is, through the twin conductor cord 31 and the connecting plug 33.

The device embodying my invention thus provides relatively simple means for supporting double illuminating means on a vacuum cleaner in such manner that they shall be well protected thereby against accidental shock and bump during actual use of the vacuum cleaner.

Various modifications may be made in the device embodying my invention without departing from the spirit and scope thereof, and I desire, therefore, that only such limitations shall be placed thereon as are imposed by the prior art or are set forth in the appended claims.

I claim as my invention:

1. In a vacuum cleaner including a motor housing and a nozzle casing secured together, an auxiliary open-front tubular casing on the cleaner having an annular shoulder therein, a lamp-supporting assembly in the auxiliary casing secured against the annular shoulder and including a forwardly extending spring latch, a dished reflector around and back of the lamp, a lens in front of the lamp and a tubular securing means for the lens held in its proper operative position by the spring latch.

2. In combination with a vacuum cleaner including a nozzle casing, an auxiliary open-front tubular casing on the nozzle casing having an inner and an outer annular shoulder in the tubular casing, a lamp-supporting structure in the auxiliary casing and having an annular flange secured against the inner shoulder, said lamp-supporting structure including a forwardly extending spring latch secured against the annular flange, a reflector having an outer flange located against the outer annular shoulder of the tubular casing, a lens in front of the lamp, a tubular support for the lens having its rear edge abutting against the outer flange of the reflector to hold it in place and having also a portion interfitting with the spring latch to be held thereby.

3. In combination with a vacuum cleaner including a nozzle casing, an auxiliary open-front tubular casing on the nozzle casing having an inner and an outer annular shoulder in the tubular casing, a lamp-supporting structure in the auxiliary casing and having an annular flange secured against the inner shoulder, a dished reflector having a flat outer peripheral portion abutting against the outer shoulder in the tubular casing, a lens in front of the lamp-supporting structure, a tubular support for the lens having its rear edge located against the outer peripheral portion of the dished reflector and a spring latch having its rear end secured against the annular flange of the lamp-supporting structure and having its forward end interfitting with the tubular lens support to hold it in its proper operative position.

LEWIS C. PACKER.
